UNITED STATES PATENT OFFICE

BRUNO PECKELHOFF, OF RAHLSTEDT, NEAR HAMBURG, GERMANY

FUEL BURNER

Application filed November 1, 1928, Serial No. 316,486, and in Germany November 9, 1927.

Liquid fuels in trade or industrial workings or on ships are burnt now almost exclusively in nozzle burners. As the nozzles are easily choked by impurities in the fuel, they 5 require careful attention. The burning of cheap non-purified oils in nozzle burners is impossible. Owing to the great quantity of air required for atomization of the fuel, nozzle burners always work with a large 10 excess of air, whereby the efficiency is reduced and in boiler installations or industrial melting installations, oxidation of the material heated is assisted.

In the hitherto known oil firing devices 15 utilizing an open burning cup, fluctuation of the oil level produces an irregular gasification and therefore bad combustion, and therefore for portable installations, for instance as employed on ships or locomotives, 20 such devices are unsuitable. The direction of burning of the flame is determined only by the horizontal position of the oil level.

The object of the present invention is to 25 eliminate these drawbacks. The flame can be introduced into the furnace combustion chamber in any desired direction. Due to gyroscopic movement of the burner cup, either individually or conjointly with the air inlets, 30 a thorough mixing of gas and air takes place, ensuring high efficiency of the oil firing installation, and high flame temperature. Any heavy oils, non-purified waste oils or even fuels in the form of dust, can be burnt.

The construction of this novel oil firing 35 installation can be of the most varied kinds. Two constructions are illustrated by way of example in the accompanying drawing.

Figure 1 shows a burner installation in 40 which the air required is supplied by a separate fan, whilst in the installation illustrated in

Figure 2 the required air is drawn in through the burner cup formed into a fan and forced into the combustion chamber.

45 The oil burner shown in Figure 1 com-

prises the annular burner cup *a* which is secured to the spindle *b*. The spindle *b* is journaled in the machine casing and is preferably driven by an electric motor *c* located adjacent one end thereof. The opposite end 50 of the spindle is fitted within a hub *b'* extending from the burner cup *a*, this hub being drilled to receive a pipe *f* which communicates with the hollow interior of the spindle *b*. The oil is conveyed by means of the 55 pump *e* through the hollow spindle *b* and the pipe *f* into the burner cup *a*. Through the branch *g* is admitted the air under pressure which flows as atomizing air through the nozzles *h*, and as additional air for combustion, through the nozzles *i*. The supply of air is regulated by means of the throttle valve *j*. Any overflowing oil is caught by the 60 cup *k* and returned through the discharge pipe *l* to the fuel tank. Inspection holes or 65 hand holes are marked *n*.

In Figure 2, *o* is the burner cup, *p* the spindle, *q* the motor, *r* the pump, *s* the oil pipe, *t* the air suction holes, *u* the fan blades for the gasifying air, *v* the fan blades for the 70 additional combustion air, *w* the nozzles for the gasifying air, and *x* the nozzles for the combustion air. The regulation of the air is effected by means of the slide valve *y*.

The working of the oil burner is as follows: 75

The burner cup *a*, Figure 1, when at rest, is filled with oil through the lateral hand holes *n*. After the oil has been ignited, and the burner cup heated to a sufficient extent, the motor *c* is started. Owing to the centrifugal force, the oil is uniformly distributed 80 over the whole burner cup.

More oil and air is then supplied. The air escaping from the inner nozzle openings *h*, passes over the fuel surface and gasifies the 85 oil. The gas mixture passes into the air current entering through the outer nozzles. Owing to the rotary motion of the nozzles and of the gas current, a thorough eddying or mixing takes place, whereby the gas burns 90

with a high temperature. The gyrating movement of the gas-air mixture is transmitted to the flame, owing to which a strong transmission of heat to the surrounding boiler or furnace parts is ensured, and therefore a high efficiency of the furnace.

The regulation of the flame is effected by a correspondingly greater or smaller oil and air supply. The more oil is supplied, the greater becomes the fuel surface, and the stronger the gasification.

A particularly easy and uniform gasification is obtained in this novel oil burner due to the fact that the specifically lighter fuel particles are always forced by the centrifugal force inward towards the surface so that they become easily and uniformly gasified. The newly supplied cold fuel particles are specifically heavier and will always be disposed round the outside of the burner cup, arriving at the inner surface only after a gradual heating. In the hitherto known oil firing installations having open burner cups, the newly admitted fuel owing to the speed of its inflow, is always initially projected to the surface and the gasification is then irregular.

If the burner is to be stopped, it is merely necessary to shut off the supply of oil. When all the oil in the cup is burnt, the motor *c* can be stopped.

The working of the firing installation according to Figure 2 is similar to that shown in Figure 1. Whilst in Figure 1, the air is supplied by a separate fan, in Figure 2 the burner cup is made at the same time into a fan. Namely the atomizing air as well as the additional combustion air is drawn through the built-in fan blades and supplied to the combustion chamber.

Having thus described the invention what is claimed as new and desired to be secured by Letters Patent is:

1. In a fuel burner, the combination with a rotating annular cup of substantially U shaped cross-section having the legs of the U directed toward the axis of rotation of the cup for receiving and retaining liquid fuel therein, of means for causing a blast of air to impinge on the surface of the fuel to effect gasification of the same, whereby the lighter and more readily gasifiable particles of fuel only are subjected to the action of the impinging blast of air, said means comprising a fan and a plurality of outwardly directed nozzles located within said cup and rotatable therewith.

2. In a fuel burner, the combination with a rotating annular cup of substantially U shaped cross-section having the legs of the U directed toward the axis of rotation of the cup for receiving and retaining liquid fuel therein, of means for causing a blast of air to impinge on the surface of the fuel to effect gasification of the same, whereby the lighter

and more readily gasifiable particles of fuel only are subjected to the action of the impinging blast of air, said means comprising a fan and a plurality of outwardly directed nozzles located within said cup and rotatable therewith, and means disposed outwardly of said cup and carried thereby for directing additional air currents into the gasified fuel discharged from the cup.

In testimony whereof I have signed my name to this specification.

BRUNO PECKELHOFF.
